UNITED STATES PATENT OFFICE

2,683,595

WIDE-RANGE MUFFLE TYPE OVEN FURNACE

John Wallerius, Glen Ellyn, and Harry E. Leccey,
Oak Park, Ill., assignors to Sunbeam Corpora-
tion, Chicago, Ill., a corporation of Illinois

Application August 24, 1949, Serial No. 112,061

1 Claim. (Cl. 263—41)

1
This invention relates to furnaces and more particularly to small muffle furnaces of the gas fired type.

Although annealing, normalizing, carburizing, forging, and miscellaneous heat treating operations are done to some extent in most shops, the major heat treating operation is the "hardening" of carbon steels. Ordinarily this consists of three operations: hardening, quenching, and tempering. In general to harden steel, it is first heated to a temperature approximately 25 to 75 degrees Fahrenheit above its critical range (approximately 1450 degrees to 1650 degrees Fahrenheit for carbon steels, and 1800 degrees to 2400 degrees Fahrenheit for the higher alloy and high speed steels). After being heated to this temperature the steel is quenched or cooled rapidly in oil, water, brine, air or similar cooling medium. The tempering operation consists of reheating the steel after the hardening and quenching steps to a temperature below the lower limit of the critical range. This relieves hardening strains and stresses and effects desired physical properties in the steel. The quenching and tempering steps should follow as soon as possible after the hardening process. Thus for ordinary steels, heretofore two furnaces have been required for treating them; one furnace having an operating temperature between 1400 degrees and 1800 degrees Fahrenheit for heating the steel in the hardening step, and a second furnace having a temperature between 300 degrees and 800 degrees Fahrenheit for heating the steel after it is quenched to temper it.

In the case of high speed alloy steels, the correct hardening temperature is from 1800 degrees to 2400 degrees Fahrenheit. Because there is a likelihood of cracking or damaging the work if it is placed directly in a furnace at this high temperature it is necessary to pre-heat the work in furnaces having an operating temperature between 1400 degrees and 1600 degrees Fahrenheit. Since the steps of preheating, hardening, quenching and tempering are all done practically simultaneously, it is necessary therefore in the handling of high speed and high alloy steels to provide three furnaces; one for the preheating operation having an operating temperature between 1400 degrees and 1600 degrees Fahrenheit, one for the hardening operation having an operating temperature between 1800 degrees and 2400 degrees Fahrenheit, and one for the tempering operation having an operating temperature between approximately 400 degrees and 1200 degrees Fahrenheit.

2
From the above it will be seen that the temperature range in the heat treating of steels varies from approximately 300 degrees to 2400 degrees Fahrenheit. Heretofore gas fired furnaces have not been satisfactory for operation throughout this temperature range. Accordingly as stated above, separate furnaces have been required for different temperature ranges depending upon the particular step of the heat treating process involved. Because two and three furnaces are usually required in the heat treating of steels, a smaller manufacturer is somewhat handicapped by the fact that a plurality of furnaces take up a considerable amount of space in his factory and require the investment of a considerable amount of capital. Accordingly many small manufacturers have not had installations whereby they could satisfactorily heat treat steels, particularly high alloy steels.

20
An object of the invention is the provision of a novel gas fired furnace of the above character that is capable of operating throughout the temperature range required for pre-heating, hardening and tempering carbon and high alloy steels.

25
Another object of the invention is the provision of a furnace of the above character having means for readily converting the furnace from a semi-muffle to a muffle furnace.

Another object of the invention is the provision of a furnace of the above character having novel burners for supplying heat to the furnace.

Another object of the invention is the provision of a furnace of the above character having novel means for igniting the burners.

35
Another object of the invention is the provision of a furnace of the above character whereby the atmosphere can be changed from a reducing to an oxidizing atmosphere.

40
Another object of the invention is the provision of a furnace of the above character which can be rapidly changed from one temperature to another temperature throughout its range of operation.

45
Another object of the invention is the provision of a furnace operable over an extremely wide range of temperatures that can be set to operate at any intermediate temperature.

50
Another object of the invention is the provision of a furnace of the above character wherein in heat treating processes formerly requiring a plurality of furnaces can be effected in a single furnace.

Another object of the invention is the provision of a furnace of the above character that is simple in construction, that is highly effective

for the purpose intended, that is rugged and that is relatively inexpensive to produce.

Other objects and advantages of the invention will become apparent from the following detailed description taken in connection with the accompanying drawings, in which—

Figure 1 is a front elevational view of a furnace embodying the present invention with a portion cutaway to show details of construction;

Fig. 2 is a sectional view of the furnace taken along the section line 2—2 of Figure 1;

Fig. 3 is a plan view of the furnace shown in Figure 1;

Fig. 4 is a sectional view taken substantially along the line 4—4 of Fig. 3;

Fig. 5 is an enlarged fragmentary sectional view of the furnace through one of the burners showing the details of construction, and

Fig. 6 is a sectional view taken substantially along the line 6—6 of Fig. 5.

Referring now to the drawings, the invention is shown embodied in a small furnace comprising a generally circular heating chamber 11, an oven unit for containing a workpiece 13 disposed in the chamber 11 and at least one burner 14 on each side of the chamber 11 disposed below the oven unit and mounted so that the products of combustion and the heat from the burner are directed into the chamber 11 in a manner to be directed against the wall on the opposite side of the chamber so as to swirl about the oven unit.

As best seen in Figs. 2 and 4 the chamber 11 is defined by a horizontal sleeve 16, the walls of which are formed by arcuate sections 17 interconnected by tongue and groove joints 18. At opposite ends of the sleeve 16 are disc shaped end portions 19 and 21. Each of the end portions 19 and 21 is formed with an annular groove 22 shaped to receive an annular tongue 23 formed on the axial faces of the sleeve 16. The sections 17 and end portions 19 and 21 may be formed from any suitable refractory material. A sleeve of insulating material 24 envelopes the peripheries of the end portions 19 and 21 and the sleeve portion 16 and a suitable sheathing of steel 26 surrounds the insulating material 24. At the rear end of the furnace the disc 21 is covered with a layer of insulating material 27. A steel end cap 28 formed with an annular flange 29 shaped to telescope over the rear end of the sheathing 26 forms a cover for the rear end of the furnace and maintains the layer of insulating material 27 in side by side relation with the disc 21. The forward end portion 19 is formed with an opening 32 defined by a flat bottom portion and an arched top portion shaped to receive and support a sleeve portion 33 having an opening 34 of conventional configuration for placing articles in and removing them from the chamber 11. The sleeve 33 projects beyond the outer face of the end portion 19 and is supported at its outer end by a support member 31 of refractory material in side-by-side relation with the bottom portion of the end portion 19. The outer axial face of the sleeve 33 is disposed in a plane inclined with respect to the vertical axis of the furnace as shown in Fig. 2 to provide a mounting for a door 36 as disclosed in Patent No. 2,270,484, issued January 20, 1942. A layer of insulating material 37 is disposed in side-by-side relation with the member 31 and the top portion of the end 19. A cap 38 having a flange portion 39 shaped to telescope over the forward end of the sheathing 26 forms a cover for the front of the furnace and maintains the layer of insulating

material 37 in its assembled relation. Suitable tie rods extend between the caps 28 and 38 and secure the component parts of the furnace in their assembled relation. The furnace may be mounted on any suitable stand 42, a portion 5 of the latter being shown herein.

The door 36 normally covers the opening 34 and is arranged to be moved vertically to uncover the opening 34 to permit access to the chamber 11. For this purpose the top of the door is connected to cables 43 trained over spaced pulleys 44 supported on a shaft 46 at the forward end of the furnace. The latter is supported by spaced brackets 47 mounted on the top of the furnace as shown in Figs. 1 and 3. One end of the shaft 46 is formed as a crank 49. At the rear end of the furnace the cables 43 pass over spaced sheaves 51 mounted on a shaft 52 supported by the brackets 47. A weight 53 at the rear end of the furnace is connected to the cables 43 and provides a counterbalance for the door 36. By rotating the crank 49 in one direction the door may be raised and by rotating the crank in the opposite direction the door may be lowered.

One aspect of the invention is concerned with novel means disposed in the furnace whereby the furnace can be readily converted from a full muffle furnace to a semi-muffle furnace. For this purpose, as best shown in Figs. 2 and 4, the oven unit is formed in two parts; the base part 54 and a cover part 56. The base part 54 in effect defines a flat hearth which is supported at the rear end of the chamber 11 by the lower side wall defining the recess 57 formed in the end portion 21 and at the front end of the chamber by the bottom wall defining the opening 32 in the end 19. The upper surface of the hearth is in alignment with the bottom flat portion of the sleeve member 33 so that articles may be readily placed in or removed from the furnace. An upright 58 disposed between the bottom of the furnace and the hearth 54 forms a support for the central portion of the hearth 54. On its side edges the hearth is formed with upturned flanges 59 as best seen in Fig. 4 spaced inwardly from the sides of the chamber 11. On their extreme upper surfaces the flanges are formed with axially extending grooves 61. The cover portion 56 is shaped to be removable through the openings 32 and 34 and comprises a generally inverted U-shaped member (see Fig. 4) having a bridging portion 62 adapted to be in spaced relation with the hearth 54 and legs 63 spaced apart the distance between the flanges 59 on the hearth 54. On their extreme lower ends the legs 63 are formed with axially extending tongues 64 shaped to fit in the grooves 61 formed on the flanges 59. At the rear end of the chamber 11 the cover portion 56 is received in a groove 66 formed in the end 21. At the opposite end of the chamber the cover portion 56 is disposed in the opening 32 formed in the end 19. The configuration of the cover portion 56 is such that when the tongues 64 fit in the grooves 61, the outer walls of the cover portion fit snugly in side by side relation with the side walls defining the opening 32, yet permit the cover portion to be withdrawn from the chamber 11 through the openings 32 and 34.

The burners 14 are mounted on the sides of the chamber 11 as best shown in Figs. 3 and 5. Each of the burners 14 comprises a body 71 having a central passage 72, defined by an annular partition 73 formed in the body, and an annular chamber 74 surrounding the passageway 72. At

one end the passageway 72 is shaped to be connected to a gas conduit 76. At its opposite end the passageway is closed by a wall 77 having a plurality of annularly spaced ports 78. Each of the ports 78 is directed outwardly at an angle with respect to the longitudinal axis of the passageway 72. The annular passageway 74 is arranged to be in communication with an air conduit 79. At the end of the chamber 74 adjacent the furnace the body 71 is formed with a plurality of annularly arranged passageways 81 in concentric relation with the ports 78. The passageways 81 are directed inwardly toward an extension of the longitudinal axis of the passageway 72. The body 71 is formed with a mounting flange 82 having slots 83 formed on opposite sides. The slots 83 are shaped to receive bolts 84 threadable into a boss 86 secured to the external sheathing 26 of the furnace. The ports 78 and 81 are arranged to be in communication with a horizontally extending passageway 87 formed in a sleeve member 88 received in the boss 86. The passageway 87 is in communication with a passageway 88 formed in the wall of the sleeve 88. The passageway 88 opens into the chamber 11 at a position below the hearth 54. As best shown in Fig. 4, four burners 14 are employed in this construction. It is to be understood however that any desired number of burners may be used. The burners are preferably disposed at staggered positions along opposite sides of the chamber 11.

Suitable means is provided for supplying gas and air to the respective burners 14. To this end the gas conduit 76 for each burner 14 is connected to a vertical conduit 90 (see Figure 1) having a burner control valve 91 connected in series therewith. Each conduit 90 is connected to a horizontal conduit 92 (see Fig. 3). The latter are connected to a common vertical conduit 93 (Figure 1) in turn connected to a horizontal gas supply line 94 beneath the furnace. A main gas shut-off valve 95 is connected in the supply line 94 for controlling the flow of gas therethrough. The air conduit 79 for each burner 14 is connected to a horizontal conduit 97 (see Fig. 3). An air control valve 98 is disposed in each conduit 79 for adjusting the flow of air to each burner 14. Each conduit 97 is in turn connected to a common horizontal conduit 99 connected to an air supply line 101. A main air shut-off valve 102 is connected in the air supply line for controlling the flow of air therethrough.

Suitable provision is made for igniting the burners 14. For this purpose the body 71 of each burner is provided with a recess 111 accessible from the top of the body 71 and shaped to be in communication with the passageway 87 when the body 71 is mounted on the side of the furnace. A cover 112 pivotally mounted at one end on the body 71 by a screw 113 is arranged to be movable between a position in which access may be had to the recess 111 and a position in which the cover rests on top of the boss 86 as shown in Fig. 5 to close the recess 111. When the cover 112 is moved about its pivot to open the recess the burner may be ignited through this recess. In some instances with the cover 112 open, air may also be supplied to the burners through the recess 111, particularly under low turn-down operating conditions. A projection 114 on the cover 112 may be provided to facilitate moving the cover between its open and closed positions.

To convert the furnace from a muffle furnace to a semi-muffle furnace, it is only necessary to raise the door 36 to clear the opening 32 and 73

then grasp the cover 56 and pull it axially through the openings 32 and 34. The tongue and groove fit on both sides of the cover 56 in effect providing skidways whereby the cover may be readily removed from the chamber 11. The end wall mountings for the base and cover insure that when the cover 56 is disposed in the chamber 11, as shown in Fig. 2, it is in sealed relation with respect to the chamber 11 and that the products of combustion from the chamber 11 cannot get into the interior of the muffle. Where desired a suitable atmosphere may be introduced into the muffle through an opening 115 formed in the end 21 of the chamber. An opening 116 in the door 36 permits inspection of the interior of the oven.

The operation of the furnace is readily apparent from the foregoing but may be summarized as follows: The gas and air valves 91 and 98 are adjusted so that the proper fuel mixture flows from the body 71 into the passageway 87. The cover 112 is moved to uncover the recess 111 and the burner is lighted by a match or the like. Thereafter the air and gas valves are adjusted so that a fuel mixture results that gives a pre-selected temperature in the chamber 11. Fig. 5 shows how the flame of the burner appears when the desired temperature in the chamber 11 is relatively low. The air from the annular ports 81 is directed inwardly toward the axis of the passageway 87. This tends to cause the gas flame to have a conical shape with the base of the flame being adjacent the burner. The products of combustion and heat are directed into the furnace beneath the hearth 54 and against the opposite side of the wall of the furnace. The products of combustion are thence directed upwardly around the hearth following the curvature of the inside of the walls of the chamber. Thus in effect the products of combustion and heat waves are caused to swirl about the hearth. As shown in Fig. 5 the flame projects only a short distance into the passage 87 from the end of the burner.

When a higher temperature is desired in the furnace the fuel mixture is made richer so that the flame extends into the chamber 11 and follows the curvature of the walls of the chamber in the manner described for the products of combustion when the flame is low. As shown in Fig. 4 when the fuel is adjusted for a high temperature in the chamber 11 the flames line the inside of the chamber 11 and swirl about the interior of the chamber. The arrangement of the ports 81 and 78 insures that the air and gas are thoroughly mixed, the intermixture taking place adjacent the end of the body 71 and in the passageway 87. Thus in effect this construction provides a 100 percent primary air burner. This construction permits of good flame control which is not true of constructions using pre-mixed gases. For example, in pre-mixed gaseous fuels on extremely low turn down the flame will backfire or blow off. With this construction the burners may operate without air being supplied through the ports 81. Because a thorough intermixing of the air and gas is assured in this construction these burners are highly efficient.

The above construction provides a furnace that may operate satisfactorily at any temperature from 300 degrees Fahrenheit to 2400 degrees Fahrenheit. This construction permits of rapid heating from relatively low temperatures to relatively high temperatures and permits the return of the temperature in the furnace to relatively low temperatures from relatively high temperatures very quickly. Due to the staggering

of the burners, the turbulence of the products of combustion and the flame and the cylindrical shape of the chamber 11, all parts of the chamber are uniformly heated. The above features also insure that if the temperature of the chamber 11 is changed, the temperature changes uniformly throughout the chamber. Due to the heating characteristics of this furnace; that is, wide temperature range and quick change to any pre-selected temperature, this furnace may be used for all phases of the hardening operation, including pre-heating, hardening and tempering. Thus, this construction provides a single furnace that may be used to heat treat either carbon steels or high alloy steels. By providing for ready removal and insertion of the cover 56 for the hearth this furnace can be readily changed from a semi-muffle to a full muffle furnace. This is advantageous not only because it permits the furnace to be cleaned readily but also because if the work being treated requires an atmosphere, the cover 56 may be inserted in the furnace and the atmosphere can be introduced into the furnace through the opening 115 at the rear end of the furnace. Thus, this single structure provides a multi-purpose furnace satisfactory for all phases of heat treating steels and other similar metals.

We claim:

In a furnace, the combination of a horizontally disposed sleeve having horizontally disposed passageways in the walls of the sleeve at staggered positions on opposite sides of the sleeve adjacent the bottom thereof in communication with the interior of the sleeve, end portions at opposite

ends of said sleeve to define with said sleeve a horizontally disposed chamber having a door at one end thereof, an article supporting hearth disposed in said chamber, means for supporting said hearth to space the latter from the bottom of the chamber above the passageways including means acting between the hearth and said end portions, an upper muffle portion slidably supported on said hearth and removable through said door, whereby the furnace may be readily converted from a muffle furnace to a semi-muffle furnace, and gas burners associated with each passageway to discharge the products of combustion into said chamber to cause the latter to follow the curvature of the chamber and swirl about the interior thereof.
